By Cognac, Inc., Clinton, Miles,
Attn: S.

UNITED STATES PATENT OFFICE.

HARRY O. BENTON, OF BAYONNE, NEW JERSEY, ASSIGNEE, BY MESNE ASSIGNMENTS, TO STANDARD DEVELOPMENT COMPANY, OF NEW YORK, N. Y., A CORPORATION OF DELAWARE.

LABELING DEVICE.

Application filed August 31, 1921. Serial No. 497,243.

To all whom it may concern:

Be it known that I, HARRY O. BENTON, a citizen of the United States, residing at 32 West 31st Street, Bayonne, in the county of 5 Hudson and State of New Jersey, have invented a new and useful Improvement in Labeling Devices, of which the following is a specification.

The present invention relates to improvements in labeling devices and more particularly to the label picking and applying mechanisms thereof. It will be fully understood from the following description, illustrated by the accompanying drawings, in 15 which:

Fig. 1 is a perspective view of the label picking device and associated plunger or finger for application of the label to a bottle or other article;

20 Fig. 2 is a transverse sectional view on the line 2—2 of Fig. 1;

Fig. 3 is a longitudinal sectional view on the line 3—3 of Fig. 1; and

25 Figs. 4, 5, and 6 are views illustrating somewhat diagrammatically the mode of operation of the device of the invention when in use.

Referring more particularly to the drawings, the numerals 10 and 11 designate the 30 ends of the oscillating arms supporting the picker supporting plates 12 and 13. Near each end of each of the supporting plates 12 and 13 a transverse groove or bore 14 is formed, in which slides a plunger 15, 35 which is secured by screws 16 or other suitable devices to the gum plates 17. The outer ends of the grooves or bores 14 are closed by the end plates 18, suitably secured to the supporting end plates 12 and 13. Springs 40 19 are interposed in the grooves 14 between the faces of the plates 18 and the ends of the plungers 15 and tend to force the latter inwards, so as to cause the edges of the gum plates 17 to meet centrally between the supporting plates 12 and 13. At the front and 45 back of their meeting edges, the gum plates 17 are provided with downwardly projecting lugs 20, the edges of the plates being rounded or beveled as indicated at 21 where these lugs are formed. This rounding or 50 beveling of the edges permits the gum plates to be readily wedged apart, as hereinafter set forth.

In operation, the gum plates of the picker are first coated with an adhesive by means

of a suitable roller or other device, the apparatus for accomplishing this purpose not being shown, as it is well known in the prior art and not a part of the present invention. The gum plates are then brought by a suitable movement of the picker arms 10 and 11 into contact with the back of a label, which adheres to them. By another suitable movement of the picker arms 10 and 11, the picker is brought into the position relative to 60 a bottle shown in Fig. 4, the numeral 22 indicating the label and the numeral 21 the bottle. The label-applying plunger, shown in perspective in Fig. 1, is then brought into co-operation with the picker to separate the gum plates and apply the label to the bottle. This plunger is provided with a grip finger 23, preferably of rubber and of wedge-shaped section, which is secured to a cross piece 24, the latter being 65 pivoted to a supporting arm 25. At the ends of the bar 24 are downwardly projecting separating fingers 26, the lower ends of which are wedge-shaped. These separating fingers are suitably made of metal and 70 are spaced apart so that they engage the gum plates 17 at the rounded or beveled portions 21. In so doing they separate the gum plates and permit the grip finger 23 to engage the label approximately centrally and apply it to the bottle, as shown in 75 Fig. 5. The remainder of the operation is carried out in the same manner as is customary in the art. The picker is raised relatively to the bottle, the separating fingers 26 keeping the gum plates separated while the ends of the label pass between them and finally spring into position against the bottle. The label is then wiped down upon the surface of the bottle by means of the 80 wipers 27. This operation is indicated in Fig. 6, but not being a portion of the present invention the detailed mechanism for carrying it out is not shown.

It will be readily apparent that the present invention permits the entire surface of the label to be covered with the adhesive, inasmuch as the edges of the gum plates 17 are held in close contact by the springs 19 up to the time the label is removed from 95 them.

Although the present invention has been described in connection with the specific details of an embodiment thereof, it is not intended that these details shall be regarded 100 as limiting the scope of the invention.

as limitations upon the scope of the invention, except in so far as may be included in the accompanying claims.

I claim:

- 5 1. A label picker comprising spaced supporting means, grooved supporting members rigidly secured to said supporting means, and gum plates slidably mounted thereon in said grooves, said gum plates normally meeting between the supporting members.
- 10 2. A label picker comprising spaced supporting plates, gum plates slidably mounted thereon, and means forcing the edges of said gum plates into contact with each other, said means permitting forced separation of the edges of said gum plates.
- 15 3. A label picker comprising spaced supporting plates, grooves formed in said supporting plates, gum plates resting on said supporting plates, said gum plates being provided with plungers slidable in said grooves, and springs in said grooves acting upon said plungers to force the edges of the gum plates to meet.
- 20 4. In a labeling device, in combination, a label picker having spaced supporting plates, gum plates slidably mounted upon said supporting plates, said gum plates having meet-

ing edges and being capable of being forcibly separated, and a label applying device, 30 said device being provided with means for separating the gum plates and means capable of passing between said spaced gum plates for carrying a label therebetween.

5. In a labeling device, in combination, a 35 label picker comprising movable plates having their edges normally in engagement and a label applying plunger, said plunger having a separating finger adapted to wedge apart and space said movable plates and a 40 grip finger adapted to pass between the separated plates.

6. In a labeling device, in combination, a 45 label picker comprising movable plates having their edges normally in engagement, end portions of said edges being rounded, and a label applying plunger having a supporting bar, separating fingers secured thereto having wedge-shaped ends adapted to engage the rounded portions of the edges of said 50 movable plates and thereby separate them, and a grip finger secured to said cross bar between said plungers and adapted to pass between the separated plates.

HARRY O. BENTON.
